Attorney.

UNITED STATES PATENT OFFICE.

HEZEKIAH H. TURNER, OF TISKILWA, ILLINOIS.

WAGON END-GATE.

SPECIFICATION forming part of Letters Patent No. 331,744, dated December 1, 1885.

Application filed September 4, 1885. Serial No. 176,139. (No model.)

To all whom it may concern:

Be it known that I, HEZEKIAH H. TURNER, a citizen of the United States, residing at Tiskilwa, in the county of Bureau and State 5 of Illinois, have invented certain new and useful Improvements in End-Gates; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 My invention serves the double purpose of wagon end-gate and shoveling-board, and is made attachable to any ordinary wagon.

The accompanying drawings illustrate the nature of my invention, reference being made 20 to its various parts by letters, similar letters denoting corresponding parts in the different views.

Figure 1 of the drawings is a detailed perspective view of the invention, the gate being 25 open. Fig. 2 is a rear elevation of same with the gate closed.

The bar A and posts a a form the frame of the invention.

B B are vertical bars parallel to and a few 30 inches in front of the posts a a, being connected to said posts by the straps b b. The straps b b are fixed to the bars B B, but are secured to the posts a a by bolts and nuts, that end of each strap having several bolt-holes, so that 35 the bars B B may be set nearer to or farther from the parts a a, as occasion may require.

C is the gate, connected to the bar A by 40 hinges c c. Any preferred hinge may be used instead of those shown in the drawings. D 45 are side-boards attached to the gate C. Two chains, E E, connect the gate C to the posts a a, and support it at any desired inclination. Two staples, F F, project backward from the posts a a, and when the gate C is closed appear at the rear of the gate, having passed through the holes d d in the said gate.

A lever, G, bolted to the gate, actuates the rods g g, which are made to enter the staples F F and lock the gate.

To attach this invention to any wagon, it is 50 only necessary that two vertical cleats be fastened to the inside of the wagon-bed, near the rear end, so that when the gate is set in position the bars B B shall stand in front of said cleats, and the posts a a be brought close 55 against the rear edge of the wagon-bed. This is effected by means of the adjustable straps b b. The gate C is slightly wider than the wagon-bed, and when the gate is closed the side-boards D D pass outside the bed suffi- 60 ciently to allow the chains E E to hang between them and the bed at either side.

When the end-gate is in position, the bars B B rest against the front edge of the vertical cleats inside the rear end of the wagon-bed, 65 by which means it is kept in place.

My invention is found especially useful in unloading such commodities as require shoveling, overcoming the difficulty of reaching the bed-bottom with the shovel, as by lowering the gate the bed-bottom is virtually extended beyond the load in the wagon, and, while it receives such part of the load as may roll out upon it, also offers a standing-place 70 for the shoveler.

I am aware that hinged end-gates are not new, and do not broadly claim such as my invention.

What I claim, and desire to secure by Letters Patent of the United States, is—

An end-gate formed of a bar, A, posts a a, vertical bars B B, straps b b, bolts e e, gate C, having the sides D D and holes d d, hinges c c, chains E E, lever G, rods g g, and staples F F, as herein set forth.

In testimony whereof I affix my signature in presence of two witnesses.

HEZEKIAH H. TURNER.
